UNITED STATES PATENT OFFICE.

JOSHUA MERRILL, OF DEDHAM, MASSACHUSETTS.

DESIGN FOR A DIE.

44,874.

Specification for Design.

Patented Nov. 11, 1913.

Application filed August 11, 1913. Serial No. 784,264. Term of patent 7 years.

To all whom it may concern:

Be it known that I, JOSHUA MERRILL, a citizen of the United States, residing at Dedham, in the county of Norfolk and State of Massachusetts, have invented a new, original, and ornamental Design for Dice, of which the following is a specification, reference being had to the accompanying drawing, forming part thereof.

In the drawings, Figure 1 is a top plan view of a die embodying my ornamental de-

sign; Fig. 2 is a bottom plan view thereof; Fig. 3 is a front elevation; Fig. 4 is a rear elevation; Fig. 5 is a right-hand side elevation. Fig. 6 is a left-hand side elevation.

I claim:

The ornamental design for a die, as shown.

JOSHUA MERRILL.
